DOWN INDICATOR

Gustaf H. Rosenboom and Virgil E. Simmons,
Kalama, Wash.

Application July 24, 1939, Serial No. 286,062

4 Claims. (Cl. 40—65)

This invention relates generally to sporting goods, and particularly to down indicators for use in connection with football games.

The main object of this invention is to provide a visible indicator by means of which the linesman may acquaint the spectators with the number of "downs."

The second object is to construct an indicator by means of which the linesman can easily indicate the "down" by means of unusually large numerals ranging from 1 to 4, the various numerals having distinctly different backgrounds, reference being made especially to the colors thereof.

The third object is to so construct the operating mechanism that a single movement by the operator will cause the previous "down" number to be cancelled and the new "down" number to be exposed.

The fourth object is to so construct the device that it will be easy to handle and transport and will not easily be rendered inoperative by rough usage.

These and other objects are accomplished in the manner set forth in the following specification as illustrated in the accompanying drawing, in which:

Fig. 1 is a side elevation of the device showing the rod portion shortened.

Fig. 2 is an enlarged side elevation of one of the indicator units.

Fig. 3 is a section taken along the line 3—3 in Fig. 1.

Fig. 4 is a section taken along the line 4—4 in Fig. 1.

Fig. 5 is a side elevation of the keyboard.

Fig. 6 is a fragmentary section taken along the line 6—6 in Fig. 5.

Fig. 7 is a fragmentary section of the device showing all of the indicators cancelled.

Fig. 8 is a fragmentary section taken along the line 8—8 in Fig. 6.

Similar numerals refer to similar parts throughout the several views.

Referring in detail to the drawing, there is shown a linesman's rod 10 near the upper end of which is formed a base 11 upon which is mounted an opaque casing 12. Within the casing 12 are disposed the concentric cylinders 13, 14, 15 and 16, all of which are slidably along the axis of the rod 10. The cylinders 13 to 16 have indicated thereon the numerals 17 which range from 1 to 4 respectively, the numeral 4 being on the cylinder 16.

Each of the cylinders 13 to 16 has depending therefrom an operating bar 18. To the bars 18

are attached the keys 19, 20, 21 and 22 which are adapted to slide in the slots 23 in the keyboard 24 which is mounted on the bracket 25, which in turn is secured to the rod 10. Each of the keys 19, 20, 21 and 22 is fastened to a slide 26 which operates within its respective slot 23, the flattened end 27 of the bar 18 forming the front bearing surface and the angle member 28 forming the rear bearing surface.

The upper end 29 of the member 26 is bifurcated as shown in Fig. 8 to receive the spring urged finger 30 which normally rests upon the angle member 28.

Behind the keyboard 24 is mounted an elongated pawl which is pivotal on the shaft 32. The pawl 31 is urged toward the angle 28 by means of the spring 33. The pawl 31 is keyed to the shaft 32 as is the lever 34 which is connected by means of a rod 35 to a bell crank key release lever 36.

Within the casing 12 is disposed a battery 37 whose leads 38 and 39 are connected to the springs 40 whose upper ends are attached to the U-shaped member 41 on which are mounted the lamps 42 which are energized by the battery 37 under the control of the switch 43.

On the member 41 is mounted the cap 44 which is urged downwardly against any or all of the members 13 to 16 by means of the springs 39 and 40. A guide rod 45 is slidably mounted in the upper end of the rod 10 and is secured by means of the screw 46 to the cap 44.

The operation of the device is as follows:

The device is normally in the position shown in Fig. 7 in which no "down" indicating numerals are visible. However, if the linesman wishes to indicate that there is a first "down," he merely moves the key 19 to its uppermost position which movement causes the pawl 31 to move out of the way and again return to its position of rest on the underside of the angle member 28, as shown in Fig. 6, holding the key 19 in an uppermost position. Since the key 19 is attached by means of the bar 18 to the cylinder 13 which carries the numeral 1 preferably on four sides, it can be seen that this numeral will now be visible. In travelling upwards the cylinder 13 carries with it the cap 44. If the game is played at night and illumination is desirable, this is obtained by the use of the switch 43 which permits the battery 37 to energize the lamps 42.

Now if the operator wishes to indicate the second "down," he merely raises the key 20. As it travels upward, the finger 30 contacts the pawl 31 causing it to move farther than it would be

moved by the mere passing of the member 28 and thereby releasing the key 19 and permitting it with its cylinder 13 to return to a lowermost position.

5 It is desirable to provide a resilient cushion 47 at the bottom of the casing 12 to absorb the shock of the falling cylinder.

If it is desired to clear the keyboard, for example after a touchdown is made, the linesman 10 needs merely to operate the lever 36 in a manner to cause the pawl 31 to release whichever key 19 to 22 is elevated, restoring the device to the position shown in Fig. 7.

15 While the release key 36 is shown lower than the other keys and operated in a different manner, it is clear that any convenient form of release mechanism could be used without departing from the spirit of this invention.

We are, of course, aware that various forms 20 of indicating devices have been constructed in the past, and it is therefore not our desire to cover such devices broadly, but we do intend to cover all such forms and modifications thereof as fall fairly within the appended claims.

25 We claim:

1. In an apparatus of the class described, the combination of a linesman's rod having a cylindrical casing disposed near the upper end thereof, a plurality of colored transparent cylinders 30 telescopically mounted within said casing and slideable with relation thereto, each of said cylinders having a plurality of "down" numerals indicated thereon, the numbers of any one of said cylinders being visible when raised above said casing, means for selectively elevating the various cylinders and a cap for covering all of said cylinders and casing having a spring for urging same downwardly.

2. A device of the class described consisting of an upright linesman's rod, a cylindrical casing mounted near the upper end of said rod, a plurality of concentric colored transparencies mounted in said casing and vertically slideable with relation thereto, a cap adapted to form a yieldable cover for said casing or for any of said transparencies when in an elevated position, means of selectively elevating said transparencies and means for releasing said raised transparencies and returning same to a concealed position within the casing. 5

10 3. The apparatus described in claim 2, together with means for illuminating the interior of said transparencies. 15

4. In a device of the class described, the combination of an upright linesman's rod, a cylindrical casing encircling said rod near the upper end thereof and coaxial therewith, a cap for said casing having a guide rod thereon adapted to 20 slide within said linesman's rod, a spring for urging said cap in a closing direction, a plurality of colored transparencies telescopically disposed around the axis of said linesman's rod, each of said members having the number of a "down" 25 indicated thereon, a keyboard associated with said linesman's rod having slideable key members mounted therein, each of said keys being connected to its respective numbered cylinder whereby said cylinders may be selectively raised, a 30 latch for holding the various cylinders in a supported position and a separate release mechanism provided with an excess movement whereby any raised cylinder may be lowered before a subsequent cylinder is raised. 35
